Primary Examiner — Andrew Kerr*Assistant Examiner* — Chariton Alexakis(74) *Attorney, Agent, or Firm* — Thomas Coester
Intellectual Property(57) **CLAIM**

The ornamental design for a packaging for a toy as shown and described.

DESCRIPTION

FIG. 1 is a front, left and top perspective view of packaging for a toy, showing our new design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is perspective view thereof in an open configuration. The dot-dot-dash broken line shown in FIG. 9 represents the direction of the assembly and forms no part of the claimed design.
